(57) **CLAIM**

The ornamental design for a low profile mounting bracket for structure, as shown and described.

DESCRIPTION

FIG. 1 is a perspective view of a low profile mounting bracket for structure in accordance with the present invention;

FIG. 2 is a back view of the low profile mounting bracket for structure;

FIG. 3 is a front view of the low profile mounting bracket for structure;

FIG. 4 is a right side view of the low profile mounting bracket for structure, the left side view being a mirror image thereof;

FIG. 5 is a top view of the low profile mounting bracket for structure; and,

FIG. 6 is a bottom view of the low profile mounting bracket for structure.
